MANIFOLDING

Charles W. Potter, Waltham, Mass.

Application December 3, 1936, Serial No. 114,045

7 Claims. (Cl. 282—12)

This invention relates to manifolding and more specifically to manifolding supplies of the continuous strip type, designed for use in typewriting and similar machines for producing a plurality of copies on each operation.

Heretofore, in the production of manifold supplies of the above character, it has been customary to provide a plurality of continuous strips of paper with a continuous series of forms printed thereon and to arrange the strips in superposed relation with continuous strips of transfer material interleaved in order to produce, when the supplies are used in a machine, a plurality of record copies in one operation. It has been customary also to provide the record and transfer strips with weakened or perforated lines between the forms and to fold the superposed strips, both record and transfer, in a zigzag manner by breaking the strips at the weakened or perforated lines. This method of folding forms a compact pile of the supplies, commonly termed a "flat pack," descriptive of its appearance.

In the use of supplies of this kind in a typewriting machine, the superposed strips are fed through the machine from a flat pack supply, and, as each set of forms is filled out, it is fed out of the machine and then torn off along the weakened or perforated lines, after which the transfer sheets are removed from between the record sheets. In such use, however, the sheets are apt to get out of register with each other during the feeding through the machine, requiring more or less continual attention from the operator for realignment, which slows down the work. Furthermore, after a set of filled forms has been separated from the strips, the removal of the transfer sheets therefrom involves a further loss of time on the part of the operator. These difficulties have a tendency to increase materially the cost of work of this character.

One of the important objects of the invention is the provision of manifolding supplies of the foregoing character in which the sheets of each set of forms are so fastened together that the record sheets are in perfect register at all times, thereby insuring that the writing on the copies will be accurately placed in the forms.

Another object of the invention is the provision of means whereby after a set of forms has been separated from the continuous strips, the transfer sheets may be easily and quickly pulled out as a group from between the record sheets without disturbing the arrangement of said sheets.

Other objects of the invention will be more specifically pointed out and described hereinafter.

In the accompanying drawing illustrating the preferred form of the invention, Figure 1 is a plan view of a portion of a continuous manifold strip made in accordance with my invention and showing a plurality of sets of forms;

Fig. 2 is a transverse sectional view on line 2—2 in Figure 1; and

Fig. 3 is a side elevation showing the strip folded on weakened or perforated lines to form a flat pack.

Referring to the drawing and particularly Figure 1, there is shown a manifold strip comprising a plurality of superposed continuous strips of paper, of which strips 10, 12 and 14 are record strips, and strips 16 and 18 interleaved between the record strips are transfer strips, coated on one side with carbon or other transfer material for reproducing on strips 12 and 14 respectively whatever is written on strip 10. Although the manifold strip is shown as made up of five continuous strips, it is obvious that it may comprise a smaller or a larger number of individual strips.

The strips, preferably all, are provided with spaced apart transverse weakened or perforated lines 20, which in each strip are in register with the lines in all the other strips. The lines are spaced apart at regular intervals, dividing the manifold strip into sets of interleaved record and transfer sheets, and serve two purposes, first, for permitting the strips to be folded zigzag on said lines to form a flat pack, as shown in Figure 3, and, second, for facilitating the severance along said lines of sets of record sheets and interleaved transfer sheets.

For holding the record and transfer strips in proper register when folded and when in use, the sheets of each set are fastened together by any suitable means, such as a wire staple 24, which is located in one of the corners of each set, preferably the upper left-hand corner. The maintaining of the register between the individual strips which make up the manifold strip is of special importance when the record strips have billing or other forms printed thereon, as shown in Figure 1, in order to insure that the matter written on the ribbon copy will be reproduced on the carbon copies in the same relation to the printed matter of the forms.

To facilitate the removal of the transfer sheets from each set after it has been separated from the manifold strip, the record and transfer sheets are provided with lines of severance, permitting

them to be torn off when separated from that portion of the set in which the fastening means is positioned, and the transfer sheets are of greater width than the record sheets to provide 5 projecting edges adapted to be gripped by the fingers, preferably, these lines of severance are oblique lines 22, running in each case from the line of separation 20 adjacent the fastening means to the adjacent side edge of the sheet 10 and in close proximity to the fastening means, thereby setting apart a triangular tab 25 on the upper left-hand corner of each sheet. The record and transfer strips are preferably arranged with their left-hand side edges in register and 15 with the right-hand side edges of the transfer strips projecting outwardly from the record strips on that edge of the manifold strip opposite to the fastening means.

In separating the transfer sheets from the record sheets of a set which has been separated from the manifold strip, the corner tab 25 is gripped by the fingers of the left hand and the projecting edges of the transfer sheets with the fingers of the right hand. A slight pull will then 20 separate the transfer sheets from the tabs 25 along the lines of severance 22, and they may be pulled out; or, if preferred, the corner tab 25 may be torn off and the transfer sheets gripped and shaken out from between the record strips. 25 The first procedure has the advantage of leaving all the record sheets attached together until such time as it may be desirable to separate them, which can be done by merely tearing off the tab. 30 By setting the staple 24 close to the corner edges, the torn-off tab may be reduced to small size, so that its removal will not mutilate the sheets. The sheets are shown as provided with side filing holes 26, but these may be omitted 35 if desired, or they may be located in the upper portion of each set.

In the use of a manifold strip made in accordance with my invention, the flat pack is mounted on a suitable support at the rear of the typewriting or billing machine which is to be used for filling out the forms, and the top end of the strip is then inserted in the machine and around the platen, with the top form exposed to view. The first form is then filled in in the usual manner and the writing upon the top sheet is reproduced by the transfer material on the underlying sheets. When a set of forms has been completed, it is fed forward in the typewriter in order to advance the next set in position for writing, and the filled-in set is separated 50 from the manifold strip along the transverse lines of severance 20. The transfer sheets may then be removed as hereinbefore described.

It will be observed that in the use of a manifold strip made in accordance with my invention, perfect register of the forms in each set is assured at all times so that the operator is not obliged to waste any time in aligning the sheets before typewriting. The separation of the 55 transfer sheets from the record sheets may be performed very easily and quickly without effort or loss of time. As a result of these features, the work is speeded up and the cost of it is reduced.

70 It is to be understood that my invention is not to be limited to the precise form herein shown and described, since it may be embodied in other forms within the scope of the following claims.

What I claim is:

75 1. A manifold strip consisting of a plurality

of continuous superposed record strips and interleaved transfer strips, all of said strips having registering side edges on one side of said manifold strip and being divided at intervals by registering transverse lines of severance into sets 5 of interleaved record and transfer sheets, the sheets of each of said sets being fastened together in one corner thereof and having oblique lines of severance adjacent said fastening means permitting said sheets to be detached from said fastening means when said set is separated from said manifold strip and said transfer strips being of greater width than said record strips to provide 10 projecting side edges on that side of said manifold strip opposite said fastening means adapted 15 to be gripped for separating said transfer sheets from the record sheets and all of said strips being free of apertures.

2. A manifold strip consisting of a plurality of continuous superposed record strips and interleaved transfer strips, all of said strips having registering side edges on one side of said manifold strip and being divided at equal intervals by registering transverse lines of severance into sets of interleaved record and transfer sheets, 25 said manifold strip being folded zigzag on said lines to form a flat pack and the sheets of each of said sets being fastened together in one corner thereof and having oblique lines of severance adjacent said fastening means permitting said sheets to be detached from said fastening means when said set is separated from said manifold strip and said transfer strips being of greater width than said record strips to afford projecting 30 side edges adapted to be gripped for separating said transfer sheets from the record sheets and all of said strips being free of apertures.

3. A manifold strip consisting of a plurality of continuous superposed record strips of uniform width and interleaved transfer strips of a wider 40 uniform width, all of said strips having registering side edges on one side of said manifold strip and said transfer strips having projecting edges on the other side of said manifold strip, all of said strips being divided at equal intervals by registering transverse lines of severance into sets of interleaved record and transfer sheets, the sheets of each of said sets being stapled together in one corner thereof adjacent said registering side edges and having lines of severance adjacent said 45 fastening means permitting said sheets to be detached from said stapled portion when a set is separated from said manifold strip.

4. A manifold strip consisting of a plurality of continuous superposed record strips of uniform 55 width and interleaved transfer strips of a wider uniform width, all of said strips having registering side edges on one side of said manifold strip and said transfer strips having projecting edges on the other side of said manifold strip, all of 60 said strips being divided at equal intervals by registering transverse lines of severance into sets of interleaved record and transfer sheets, said manifold strip being folded zigzag on said lines to form a flat pack and the sheets of each of said 65 sets being fastened together in one corner thereof adjacent said registering side edges and having lines of severance adjacent said fastening means permitting said sheets to be detached from said fastening means when said set is separated 70 from said manifold strip.

5. A manifold strip consisting of a plurality of continuous superposed record strips of uniform width and interleaved transfer strips of a wider uniform width, all of said strips having register- 75

ing side edges on one side of said manifold strip and said transfer strips having projecting edges on the other side of said manifold strip, all of said strips being divided at equal intervals by 5 registering transverse lines of severance into sets of interleaved record and transfer sheets, the sheets of each of said sets being stapled together in the upper left-hand corner thereof and having oblique lines of severance adjacent said fastening means permitting, when a set is separated from manifold strip, said transfer sheets to be detached from said stapled portion without disturbing the record sheets.

6. A manifold strip consisting of a plurality of 15 continuous superposed record strips of uniform width and interleaved transfer strips of a wider uniform width, all of said strips being without apertures and having registering side edges on one side of said manifold strip and said transfer strips having projecting edges on the other side 20 of said manifold strip, all of said strips being divided at equal intervals by registering transverse lines of severance into sets of interleaved record and transfer sheets, the sheets of each of said sets being stapled together in one corner thereof

adjacent said registering side edges and having oblique lines of severance adjacent said fastening means permitting, when a set is separated from said manifold strip, said transfer sheets to be detached from said stapled portion without disturbing the record sheets. 5

7. A manifold strip consisting of a plurality of continuous superposed record strips of uniform width and interleaved transfer strips of a wider uniform width, all of said strips having registering side edges on one side of said manifold strip and said transfer strips having projecting edges on the other side of said manifold strip, all of said strips being divided at equal intervals by 10 registering transverse lines of severance into sets of interleaved record and transfer sheets and being folded zigzag on said lines to form a pack, the sheets of each of said sets being stapled together in the upper left-hand corner thereof and having oblique lines of severance adjacent said 15 fastening means permitting, when a set is separated from said manifold strip, said transfer sheets to be detached from said stapled portion without disturbing the record sheets. 20
